DESCRIPTION

FIG. 1 is a perspective view of a blade tip for an automobile glass molding and gasket removal tool showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is an enlarged perspective view of the blade tip. The broken line showing of the automobile glass molding and gasket removal tool is for illustrative purposes only and forms no part of the claimed design.

FIG. 1

FIG. 8

FIG. 2

FIG. 3

FIG. 5

FIG. 4

FIG. 6

FIG. 7
